ELECTRONIC STETHOSCOPE

Bernard B. King, Venice, Calif., assignor, by mesne assignments, to Douglas Aircraft Company, Inc., Santa Monica, Calif., a corporation of Delaware

Filed May 2, 1966, Ser. No. 2,127

Term of patent 14 years

(Cl. D83—12)

FIGURE 1 is a front elevation of an electronic stethoscope, embodying my new design;

FIGURE 2 is a side elevation as seen from the right of FIGURE 1, with portions omitted for ease of illustration;

FIGURE 3 is a rear elevational view thereof;

FIGURE 4 is a top plan view thereof, as taken along the line 4—4 indicated in FIGURE 3; and

FIGURE 5 is a bottom plan view thereof, as taken along the line 5—5 indicated in FIGURE 3.

The other side, not shown, of the electronic stethoscope with frequency and volume controls, is similar to the side which is illustrated.

The dominant features of my design reside in the portions shown in full lines.

I claim:

The ornamental design for an electronic stethoscope, substantially as shown and described.
